Application January 28, 1955, Serial No. 484,652

6 Claims. (Cl. 208—251)

This invention relates to the removal of metal contaminants from petroleum oils, and particularly as a feed preparation step for subsequent catalytic cracking of such oil. Thus, in one aspect, the present invention provides a novel process for the upgrading of petroleum feed stocks for catalytic cracking which are normally contaminated with metal compounds detrimental to a catalytic cracking operation. The invention provides a selective extraction process making possible the removal of substantial amounts of metal contaminants from a heavy petroleum oil at high yields of the treated oil. This is made possible by the use of an extraction solvent comprising pyridine or related compounds together with about 10 to 40% of water.

The principal application of this invention relates to the solvent extraction of petroleum oil fractions boiling in the gas oil boiling range, so as to upgrade these fractions for use as catalytic cracking feed. The invention entails the use of aqueous pyridine as a selective solvent for metal contaminants normally present in gas oil. The present invention is based on the discovery that aqueous pyridine is uniquely effective for selectively removing metal contaminants from catalytic cracking feed stocks with substantially no loss of hydrocarbon constituents suitable for cracking.

At the present time the process of catalytic cracking is extensively employed for converting high boiling portions of a petroleum crude oil to lighter boiling commercially valuable products including gasoline and fuel oils. The feed stock to a catalytic cracking unit ordinarily constitutes portions of a petroleum crude oil boiling above the gasoline boiling range or boiling above about 430° F. Such feed stocks may be derived by distillation from virgin crude oils or may be obtained from the products of coking residual oil fractions. Heretofore such feed stocks have normally had a final atmospheric equivalent boiling point of about 800° or 900° F. However, it is economically desirable to include the highest boiling fraction of a petroleum crude oil attainable by the vacuum distillation of atmospheric reduced crude. In this case, the feed to a catalytic cracking unit preferably includes constituents of the crude oil having an equivalent atmospheric boiling point of up to about 1100° F., or higher. Consequently, as used herein, the term "gas oil" is used to identify this portion of a crude oil boiling in the range of about 430° to 1100° F., or somewhat higher.

Attempts to extend the final boiling point of gas oil fractions used for catalytic cracking have heretofore been hampered by the presence of metal contaminants in such heavy gas oils. Among the metal contaminants present in heavy gas oils are organic compounds of nickel, vanadium and iron, which are particularly objectionable. These organic metallic compounds serve to poison the catalyst used during catalytic cracking so as to materially decrease the selectivity and life of the catalyst. Inclusion of the highest boiling gas oils as catalytic cracking feed stocks has therefore been limited by the economic loss resulting in the catalytic cracking operation due to the presence of these metal contaminants.

2

There have been many suggestions aimed at minimizing the metal contamination of heavy gas oils for catalytic cracking feed stocks. It has been known, for example, that residual petroleum oils can be deasphalted in a manner removing a large portion of metal contaminants. However, complete elimination of metal contaminants by deasphalting has not been found to be possible. It has also been found that removal of metal contaminants can be accomplished to some extent by proper fractionation of the catalytic cracking feed stocks. Again, however, this technique does not completely solve the problem, in particular, since more volatile metal contaminants cannot be removed by fractionation carried out above about the 1050-1150° F., equivalent atmospheric boiling point range.

The present invention is supported by basic research work directed to a determination of the nature of the metal contaminants present in heavy petroleum fractions. This work has established that the metal contaminants are apparently present in the form of metal porphyrins. It appears that both monomeric and polymeric metal porphyrins occur in oil and that these may vary widely in nature depending upon the nature and length of the radicals attached to the porphyrin nucleus. It has also been established that these metal contaminants can be roughly divided into a volatile and non-volatile category in which the volatile metal contaminants can be said to boil in an equivalent atmospheric boiling point range of about 1100° to 1300° F., or possibly higher. It follows from this that deasphalting and distillation of heavy petroleum fractions is unsatisfactory for complete elimination of metal contaminants since each of these processes is best adapted for removing only the non-volatile category of metal contaminants. The present invention is of particular significance in providing a technique capable of removing the volatile category of metal contaminants. The process of this invention is therefore of particular utility for the preparation of catalytic cracking feed stocks in combination with a fractionation or deasphalting operation.

The heart of the present invention entails the use of aqueous pyridine as a selective solvent for the removal of volatile metal contaminants from catalytic cracking feed stocks. The possibility of removing metal contaminants by solvent extraction has been appreciated heretofore, and it has been known that a solvent such as phenol, for example, will extract metal contaminants to some extent. However, use of such selective solvents has not appeared to be a practical procedure, since these solvents extract substantial portions of the oil being treated along with the metal contaminants. In other words, the general use of selective solvents for removal of metal contaminants has appeared prohibitively expensive due to the concomitant loss of hydrocarbon constituents suitable for cracking. In accordance with this invention, however, it has been found that extremely selective removal of metal contaminants, exclusive of any substantial removal of hydrocarbon constituents, can be achieved by employing pyridine together with critical amounts of water in the range of about 10 to 40% based on the pyridine. Thus, while pyridine alone is miscible in most oils and in any case exhibits poor selectivity for removal of metal contaminants relative to hydrocarbon constituents, aqueous pyridine exhibits remarkable selectivity for metal contaminants. This makes possible use of aqueous pyridine for extraction of metal contaminants providing treated oil fractions of substantially lower content of metal contaminants in yields well above 95%.

The nature and objects of this invention will be fully described in connection with the accompanying drawings and the following examples of the invention.

In the drawings:

Figure 1 diagrammatically illustrates a flow plan embodying the principles of this invention, while

Figure 2 graphically shows the unique properties of the particular solvent used in this invention.

In order to show the selective solvent properties of the aqueous pyridine used in this invention, reference is made to a number of experiments which were conducted employing aqueous pyridine of variable water content. In these experiments, a Bachaquero crude petroleum oil was subjected to atmospheric and vacuum reduction to obtain a residual oil boiling above 900° F. Using 100 ml. of this residual oil, the residue was extracted with 100 ml. of pyridine and varying amounts of water. Extractions were conducted in a batch manner at ambient temperatures. In order to analytically determine the presence of metal contaminants, the oil feed and oil product were scanned with a recording spectrophotometer in the visible region. It was determined that vanadium contents found by wet ash analyses could be correlated to the optical density at 573 and 536 m μ . It was furthermore found that the occurrence of other types of metal contaminants such as nickel correlated to the amount of vanadium contaminants. Consequently, in these and other experiments, the concentration of metal contaminants is reported as the optical density at the 573 m μ peak.

In a first series of experiments conducted as described, a constant oil to pyridine ratio was maintained during extraction which was conducted with variable amounts of water. In a second series of experiments, the pyridine to water ratio was kept constant while the ratio of oil to pyridine was varied. The data obtained from these experiments are shown in Table I.

* Using base line technique for each peak separately.

It will be noted from this data that in varying the amount of water present with the pyridine during extraction, the amount of oil which was extracted varied inversely with the amount of water used. Furthermore, it will be observed that the amount of metal contaminants extracted from the oil and contained in the extract phase varied appreciably in accordance with the water content of the extraction system. This is graphically illustrated in Figure 2 of the drawings which plots the data of Table I.

It is apparent from Figure 2 that the water content of pyridine is a critical factor effecting the extraction of metal contaminants. In particular, it will be observed that substantially no extraction of metal contaminants is achieved below a water concentration of about 10% based on the pyridine nor above the water concentration of about 40% based on the pyridine. Furthermore, due to the sharply peaked nature of this phenomenon, an aqueous pyridine having a water content of about 18% is uniquely effective for removing metallic contaminants in the case of the particular residual oil treated.

The data in the lower portion of Table I indicates that variation of the solvent to oil ratio, maintaining the pyridine to water ratio constant, does not appreciably change the concentration of metal contaminants in the extract phase over a wide range. In other words, the total volume of vanadium extracted appears to be proportional to the volume of solvent used.

Using these basic principles, experiments were then conducted employing an aqueous pyridine solvent. Using this solvent composition, a Tia Juana crude oil was extracted with aqueous pyridine. The extractions were conducted in a batch manner at ambient temperatures. The pyridine extract phase, obtained by phase separation after extraction, was then subjected to analyses to determine the transference of metal contaminants from the crude oil to the pyridine extract. The data obtained by these experiments are shown in Table II:

TABLE II

This data shows that the aqueous pyridine was effective in removing metal contaminants from crude oil itself.

In a similar series of experiments, a vacuum reduced residual oil obtained from a Bachaquero crude oil boiling above 900° F. was subjected to pyridine extraction. In each run 1250 cc. of residual oil was extracted with 1250 cc. of pyridine and 250 cc. of water. The extraction solvent in other words constituted aqueous pyridine having a water content of 20%. Twelve successive extractions were carried out. The results of these runs are shown in Table III:

ing one type of metal contaminants while being relatively ineffective in extracting other types of metal contaminants. The existence of this effect and the importance of it was established by the following experiment.

The Bachaquero residual oil referred to in the preceding experiment was subjected to molecular distillation to segregate the fraction boiling in the range of about 900° to 1300° F., amounting to 50 volume percent of the total residual oil. This fraction contained 79 p.p.m. of vanadium. 24.1 g. of this distillate fraction was repeatedly extracted with 30 cc. batches of pyridine containing

^a Complete separation was never obtained. This is volume of phase, not net oil.

^b All extracts diluted further with 2 vols. pyridine before optical density measurement.

^c Cumulative values in parentheses.

^d Peaks due to vanadium porphyrin.

Again, it will be seen that the aqueous pyridine was effective in extracting substantial amounts of metal contaminants from the residual oil. The data also brings out the small amounts of oil carried over into the extract phase even though complete separation of the extract phase was not attained. Thus, in run No. 7, for example, of an extract phase having a volume of 1500 cc., the oil content amounted to only 6.3 mg./cc. It will also be observed that in the successive extractions conducted, the vanadium content of the residue was reduced by substantially 30%. While successive extractions would be expected to remove somewhat greater amounts of vanadium, it is apparent that complete removal of metal contaminants from the crude oil could not be obtained by aqueous pyridine extraction. This data indicates that the aqueous pyridine was effective in extract-

5 cc. of water. The data obtained in these runs is shown in Table IV.

^a 2 cc. pyridine phase diluted with 4 cc. of pyridine for optical density measurement.

From the data of this table, it will be seen that the aqueous pyridine was effective in extracting substantially all of the metal contaminants present in the distillate fraction. Considering this data in connection with the data of Table III, it is therefore shown that aqueous pyridine exerts a selective solvent action toward volatile metal contaminants boiling up to about 1300° F. or somewhat higher. Metal contaminants boiling significantly above this range are apparently not effectively extracted by aqueous pyridine.

The present invention has been described with reference to pyridine itself and is considered of particular utility when employing this specific compound. However, alkyl substituted pyridine may be employed, and particularly the methyl substituted pyridines. This makes possible the use of mixed pyridine type compounds including crude pyridine in the process of this invention. Data obtained for such extraction agents are shown in the following table, employing the techniques described hereinbefore:

In applying this invention to extraction of heavy oil fractions, particular techniques for reducing the viscosity of the heavy oil are desirable. Difficulties are involved in determining a diluent which can be employed for this purpose without impairing the metal removing properties of the aqueous pyridine. Diluents such as isooctane or normal heptane cannot be employed, since such compounds are not soluble in aqueous pyridine and since they exert a selective solvent action toward metal porphyrins which would tend to retain these in the oil raffinate. However, it was found that aromatic compounds and particularly xylene, toluene and benzene actually improve the efficiency of metal removal and therefore can be used for reducing the viscosity of a heavy oil to be treated. Experiments demonstrating the particular utility of xylene, are shown in Table VI.

It will be seen from this data that use of xylene in the aqueous pyridine extraction of a heavy oil serves to substantially improve extraction results by decreasing the amount of oil in the extraction phase and by increasing the concentration of metal contaminants in the extract phase.

In order to fully establish the operability of this invention, a heavy gas oil obtained from a commercial vacuum distillation operation was subjected to aqueous pyridine extraction. The gas oil was a bottoms side stream derived from the vacuum distillation of mixed

San Joaquin, Sweden and West Texas crude oils and boiled in the upper part of the range of about 700° to 1200° F.

This gas oil was extracted in a countercurrent multi-stage extractor in runs employing 5 and 20 countercurrent stages of contacting. During these runs a temperature gradient was maintained along the extractor in the manner customarily employed in plant scale extractions. The results of these experiments are shown in the following Table VII.

TABLE VII

It will be observed that the aqueous pyridine served to greatly drop the content of nickel contaminants. However, due to the extremely selective nature of the solvent, treated oil was obtained in yields above 96 weight percent. In this connection, it was observed by chromatographic analysis that the loss in oil yield relates to removal of essentially no paraffins or naphthenes but only the extremely aromatic and polar materials which would be of poor cracking quality. Consequently, this data shows the particular utility of aqueous pyridine for upgrading heavy gas oil for catalytic cracking.

While the process of this invention may be embodied in a number of techniques, in refining operations, Figure 1 of the drawing illustrates a preferred embodiment of the invention. In this drawing the numeral 1 designates an atmospheric distillation tower, which may be of conventional character. A crude oil may be brought into tower 1 through line 2 wherein it is fractionated into any desired number of different boiling streams. Thus, light gases may be removed from the top of zone 1 through line 3, while higher boiling fractions such as gasoline and heating oil may be withdrawn through sidestream withdrawals 4 and 5. A reduced crude fraction which may, for example, boil above about 700° F., may be withdrawn as a bottoms product through line 6.

This reduced crude fraction may then be subjected to vacuum distillation in zone 7 with or without fractionation below the exit line 8. In distillation tower 7, a high vacuum is maintained to permit recovery of high boiling distillates without cracking. For example, operation may be adjusted to secure removal through line 8 of a heavy gas oil boiling in the range of about 450 to 1300° F. Lighter fractions may be removed through higher points of the tower including the upper withdrawal line 19, while the heaviest fraction may be withdrawn as a bottoms product through line 20. In accordance with the data described herein, the heavy gas oil stream of line 8 will include volatile metal contaminants originally present in the crude oil. Non-volatile metal contaminants will be concentrated in the residual fraction withdrawn from line 20. The heavy gas oil of line 8 is then subjected to solvent extraction in tower 9 employing aqueous pyridine introduced through line 10 as an extractive solvent. Contacting may be carried out in a countercurrent or staged extraction tower of the nature illustrated in which aqueous pyridine will drop downwardly through the tower countercurrent to the heavy gas oil. A raffinate product will then be withdrawn from the top of the extraction tower through line

75

11 comprising the treated gas oil having substantially less metal contaminant content than the gas oil of line 8. This treated gas oil is stripped in zone 18 and the pyridine-free oil is then preferably subjected to catalytic cracking in zone 12. The aqueous pyridine taken over in line 24 is condensed and recycled. The catalytic cracking may be carried out in the conventional manner employing conventional catalysts. For example, the catalyst may be of the metal oxide type and preferably will include silica-alumina, silica-magnesia, or silica gel, promoted with metal oxides which are adsorbed thereon. Typical cracking conditions are at temperatures in the range of about 750° to 1050° F., and pressures ranging from atmospheric to somewhat above atmospheric pressure.

The extract phase removed from zone 9 through line 14 will consist of the spent aqueous pyridine together with minor amounts of the gas oil introduced into zone 9. Pyridine may be recovered from this extract phase for recycle to the system by passing the extract phase to a stripping zone 15. Stripper 15 may be operated to drive water and pyridine over-head for removal and recycle through line 16 and to permit removal of the oil extract constituents through line 17.

In the conduct of solvent extraction zone 9, the extraction agent will constitute pyridine together with about 10 to 40% of water, preferably about 20% of water is employed with the pyridine constituting the extraction agent. Based on the oil to be treated, treats of about 50 to 500 volume percent may be employed, although use of about 1 to 2 times the volume of oil is preferred. It is a particular feature of this invention that the extraction can be carried out at ambient temperatures, although elevated temperatures can be employed particularly in order to decrease the viscosity of the oil aiding in effective phase separation. Again, pressure is not a critical factor in the aqueous pyridine extraction, so that atmospheric pressure or elevated pressures can be employed.

As described and as shown by the data referred to, the aqueous pyridine extraction of this invention is of particular utility to the treatment of heavy gas oils intended for catalytic cracking. In this application, the invention is applied to virgin petroleum distillates or gas oils from coking operations which distillates or gas oils boil above about 450° F., especially those above 1100° F., ranging upwardly to about 1300° F., or even higher. As emphasized, application of this invention to such a distillate fraction is particularly desirable in providing a fraction in which the metal contaminants present are of a volatile nature and are completely extractable by the aqueous pyridine. However, the invention is also of application to the treatment of the crude oil itself or to residual fractions of crude oil. In these cases, it is a particular feature to employ the process of this invention in combination with a deasphalting operation. Thus, as formerly pointed out, deasphalting may be con-

ducted so as to remove non-volatile metal contaminants so that removal of volatile contaminants by the aqueous pyridine extraction can be used in combination with deasphalting to substantially diminish or eliminate all metal contaminants.

What is claimed is:

1. A process for removing metal contaminants from high boiling fractions derived from a petroleum crude oil, including hydrocarbon constituents boiling above about 900° F., which comprises contacting said fraction with an extraction agent consisting of a compound selected from the group comprising pyridine and alkyl substituted pyridines together with about 10 to 40 parts of water per 100 parts of the pyridine, whereby metal contaminants may be removed.

2. A process for providing high quality high boiling catalytic cracking feed stock in which a reduced crude oil fraction boiling up to about 1300° F. is contacted with an aqueous pyridine having a water content of about 10 to 40 parts per 100 parts of pyridine, and recovering a raffinate product consisting of catalytic cracking feed of substantially reduced metal content.

3. The process defined by claim 1 in which the said contact is carried out in the presence of an aromatic hydrocarbon selected from the class consisting of xylene, benzene, and toluene.

4. The process defined by claim 1 in which the said extraction agent has a water content of about 20 parts per 100 parts of pyridine.

5. The process defined by claim 1 in which about 50 to 500 volume percent of extraction agent is employed per volume of the petroleum fraction.

6. A process for segregating metal contaminants from a petroleum crude oil comprising fractionating said crude oil to obtain a fraction boiling within the range of about 430° to 1300° F., whereby extractable metal contaminants are concentrated in the said fraction and thereafter contacting said fraction with an extraction agent consisting of a compound selected from the group comprising pyridine and alkyl substituted pyridines together with about 10 to 40 parts of water per 100 parts of the pyridine, whereby metal contaminants may be removed.
